FLUID SEALING DEVICE

John H. F. Stewart, Detroit, Mich.

Application January 11, 1946, Serial No. 640,516

7 Claims. (Cl. 267—1)

1

This invention relates to springs of the compression type.

Where a compression spring is required to fit in an annular space, the customary helical wire spring is ordinarily used when sufficient axial space is available. In applications where the axial space is very short in relation to the annular diameter of the spring, wave washers, Bellville springs and various stamped sheet metal devices have heretofore been used. The range of action on the latter type of springs, however, is relatively short and there is an intermediate zone within which neither the helical wire spring nor the other types mentioned will provide sufficient range of action and, at the same time, come within the available axial space.

It is an object of the present invention to provide an improved spring device which occupies less axial space than an equivalent helical spring and, at the same time, provides a greater range of action than is available from other types of springs having a short axial length.

It is a further object of the invention to provide a spring of this character comprising a flat annular base having a plurality of wire spring elements secured thereto, which elements, when subjected to compression forces, are inherently stable in the sense that there is no tendency for them to tip to one side.

Further objects and advantages of the present invention will be apparent from the following description, reference being had to the accompanying drawing wherein a preferred form of the present invention is clearly shown.

In the drawing:

Figure 1 is a top view of a spring device embodying a preferred form of the present invention.

Figure 2 is a side view of the spring shown in Figure 1.

Figure 3 is a diagrammatic top view of one of the spring elements.

Figure 4 is a diagrammatic side view of one of the spring elements.

Referring now to Figures 1 and 2, there is shown an annular base element 10, preferably formed of sheet metal, and having an L-shaped cross section to provide a flat flange 12 and an upstanding short tubular section 14. Secured to the base 10 are a plurality of one-piece wire spring elements 16. The elements 16 are formed with a flat base portion 18 curved to fit the base 10 in the plane thereof. Each element 16 at its free end is bent upwardly at an acute angle to the plane of the base, forming an active tip 20.

As shown in Figure 2, the free ends or tips 20 are curved slightly so as to present a less acute angle to the plane of the base at their ends than they do at the point where they join with the base portion 18. The spring elements 16 are secured to the base 10 in any suitable way, preferably by crimping over sections of the upstanding tubular part 14 as shown at 22. The free ends or tips may also be curved slightly radially inward, as seen in Figure 1, to provide a light frictional grip upon any male cylindrical member with which this spring device is associated. Alternatively, this feature may be omitted and the tip of the spring element may directly overlie the base portion 18, as seen in Figure 1, or they may be bent outwardly to engage a female cylindrical element with which the spring is associated.

The device as thus constructed may be mounted in any suitable annular space of short axial length and will provide compressive spring action through a substantial distance at least equal to half the free height of the device. With a helical spring of the same capacity, a much larger wire diameter would be required, and it will be evident that with even a minimum number of turns the compressed or solid length of such a spring would be much greater than the free height of the device disclosed.

Another feature of the present device concerns the characteristics of the individual spring elements 16 which are completely free from any tendencies to tip or twist with respect to the base element 10. As shown in Figures 3 and 4, the projected area of the base is a circular segment and the point of application of force is at the tip of the free end. Since these tips overlie the base area, any endwise force is supported upon a broad base and there is no tendency for the element to tip or roll with respect to base 10.

The curvature of the tip 20 which is seen in Figure 2 enables the spring elements to flex through a considerable distance when pressed by any flat annular member and, at the same time, to maintain contact with such member at the very tip of the element. Without this curvature there is a tendency for the contact point between the spring element and the adjacent abutment member to move away from the tip toward the point where the free end is joined with the base portion. By securing the spring element to the base at points which are spaced from the very ends of the base portion, some flexibility is allowed in the extended ends of the base portion permitting these ends to raise upwardly

slightly (Figure 2) as the tips of the free end 20 are depressed.

It will thus be seen that the present invention provides a spring device capable of fitting within a very short axial length, while at the same time providing a relatively large range of action.

While the form of embodiment of the invention as herein disclosed constitutes a preferred form, it is to be understood that other forms might be adopted, all coming within the scope of the claims which follow.

What is claimed is as follows:

1. An annular axially compressible spring comprising an annular base member of small axial height and a plurality of one-piece wire spring elements secured to the base at spaced locations around its periphery, each spring element having a flat base portion curved to extend along an arc of the base member and having its free ends curved back at an acute angle to overlie the base portion.

2. An annular axially compressible spring comprising an annular base member of small axial height and a plurality of one-piece wire spring elements secured to the base at spaced locations around its periphery, each spring element having a flat base portion curved to extend along an arc of the base member and having its free ends curved back at an acute angle to overlie the base portion, the free ends of the elements lying within the axial projection of the segment of said arc whereby each spring element is stably supported against tipping when subject to axial compression.

3. An annular axially compressible spring comprising an annular base member of small axial height and a plurality of one-piece wire spring elements secured to the base at spaced locations around its periphery, each spring element having a flat base portion curved arcuately to fit the base and having its free ends inclined back over the base portion at an acute angle.

4. An annular axially compressible spring comprising an annular base member of small axial height and a plurality of one-piece wire spring elements secured to the base at spaced locations around its periphery, each spring element having a flat base portion curved arcuately to fit the base

and having its free ends inclined back over the base portion at an acute angle and curved toward a less acute angle at their tips with respect to the base portion.

5. An annular axially compressible spring comprising an annular base member of small axial height and of L-shaped cross section, and a plurality of one-piece wire spring elements secured to the base at spaced locations around its periphery, each spring element having a flat base portion curved arcuately to fit the base and having its free ends inclined back over the base portion at an acute angle.

15 6. An annular axially compressible spring comprising an annular base member of small axial height and of L-shaped cross section, and a plurality of one-piece wire spring elements secured to the base at spaced locations around its periphery, each spring element having a flat base portion curved arcuately to fit the base and having its free ends inclined back over the base portion at an acute angle, the base member having portions thereof crimped over the base portions of the spring elements.

20 7. A spring element comprising a single piece of wire having a flat base portion curved in one plane to extend along the arc of an area in the general shape of a circular segment and having at least one free end portion bent out of said plane at an acute angle to the base portion with its tip lying within the perpendicular projection of said area whereby the element resists tipping when subject to compression forces perpendicular to the plane of the base.
